UNITED STATES PATENT OFFICE

JURJEN S. HIGH, OF OAKLYN MANOR, NEW JERSEY, ASSIGNOR TO WESTINGHOUSE ELECTRIC & MANUFACTURING COMPANY, A CORPORATION OF PENNSYLVANIA

ELECTRICAL TRANSLATING DEVICE

Application filed October 30, 1930. Serial No. 492,215.

My invention relates to electrical translating devices and it has particular relation to devices of the type known as loud-speakers.

5 Substantially all loud-speakers, as hitherto constructed, may be divided into three main classes, i. e., those wherein the movable element of the motor is a coil, or the like, those in which a movable metallic armature is 10 mounted to oscillate in a magnetic field and those wherein a metallic diaphragm is subjected to a varying magnetic attraction. Loud speakers of the first-mentioned class, generally known as "electrodynamic" speakers, are, for many reasons well known to those skilled in the art, acoustically superior 15 to loud speakers of the second and third classes.

Electrodynamic speakers, however, are relatively bulky and clumsy, and are quite expensive to manufacture. Furthermore, such speakers must either be provided with relatively massive field-magnets of cobalt steel, or else have a large field-winding capable of 25 being energized from a direct current source. They usually require a special input transformer for furnishing the optimum sound current and, if they are of the type having a field winding, a rectifying device is necessary 30 for converting the commercially available alternating current into direct current for the field.

The field-magnet structure of the usual electrodynamic loud speaker occupies a space 35 extending five inches, or more, rearwardly of the apex of the cone-diaphragm, necessitating the use of a deep enclosing case, which is objectionable on account of the distortion introduced by case resonance.

40 In short, electrodynamic speakers, by reason of their unavoidable bulkiness and weight, have not been at all suitable for wall mounting and, as a consequence, the majority of loud speakers of the wall-type have comprised balanced-armature motors.

It is, accordingly, an object of my invention to provide an electrodynamic loud-speaker motor particularly suitable for use in wall-type loud speakers.

50 Another object of my invention is to pro-

vide an electrodynamic loud-speaker motor that shall be much shallower, when considered axially of a conical diaphragm actuated thereby, than previously constructed motors of the same general type.

Another object of my invention is to provide an electrodynamic loud-speaker motor that shall be relatively inexpensive to manufacture.

Another object of my invention is to provide a loud-speaker motor, of the induction type, wherein the moving element is so constructed and arranged that efficient use is made of the induced currents flowing therein.

Another object of my invention is to provide a loud-speaker motor that shall be substantially unaffected by fluctuations in the current supplied to the field-winding thereof.

Another object of my invention is to provide, in a loud speaker motor, means whereby the magnetic flux arising from variable currents, representing sounds, shall be confined to a limited magnetic circuit that is substantially independent of the field-magnet, whereby the said field magnet is prevented from rapidly losing its magnetization.

Another, and more specific object of my invention, is to provide a unitary moving element and resilient support therefor suitable for use in my improved electrodynamic loud speaker.

According to my invention I provide a U-shape permanent magnet of chromium or cobalt steel, or an electromagnet, with a plurality of laminated pole-pieces. The pole-pieces closely approach one another to define a narrow air-gap in which is resiliently suspended a thin plate of non-magnetic material.

Each pole-piece is provided with a sound-current coil whereby the flux threading the thin plate may be caused to vary and, accordingly, to induce potentials therein which give rise to electric currents. The plate, which hereinafter will be designated the armature, is connected to a diaphragm of any convenient configuration, such as a cone, or the like, by means of a connecting rod soldered thereto or formed as an integral extension thereof.

The novel features that I consider charac-

teristic of my invention are set forth with particularity in the appended claims. The invention itself, however, both as to its organization and its method of operation, together with additional objects and advantages thereof, will best be understood from the following description of a specific embodiment, when read in connection with the accompanying drawings, in which:

10 Figure 1 is a plan view of a loud-speaker actuating motor comprising a preferred embodiment of my invention;

Fig. 2 is an end elevational view of the motor;

15 Fig. 3 is a side elevational view of the same;

Figs. 4 and 5 are views of an armature illustrating the manner in which electric currents are constrained to flow therein;

20 Fig. 6 is a view in perspective of an armature as disclosed in Figs. 4 and 5;

Fig. 7 is a plan view partially in section, illustrating a modification of my invention as disclosed in Fig. 1;

25 Fig. 8 is a cross sectional view along the line VIII—VIII of Fig. 7 with the diaphragm removed;

Fig. 9 is a view showing an armature structure for use in the embodiment of my invention as disclosed in Fig. 7;

30 Figs. 10 and 11 are views illustrating the manner of supporting or mounting an armature of the type disclosed in Fig. 9;

Fig. 12 is a schematic view showing a modification of the armature supporting means disclosed in Figs. 10 and 11.

The apparatus illustrated in Figs. 1, 2 and 3 comprises a U-shape permanent field magnet 1 preferably of cobalt steel or of an equivalent material. Each pole of the magnet 1 is provided with a pole-piece assembly 40 constituted by a plurality of h-shape laminations 2 of silicon steel. Each stack of laminations constituting a pole-piece is held firmly against the corresponding end of the permanent magnet by means of a clamping bolt 3 which extends through the said end and which is provided with a retaining device 4 having downwardly-bent ends 5. The laminated pole-pieces are so disposed with respect to each other that a plurality of narrow rectangular air gaps 6 and 7 are defined by the inwardly extending legs 8, 10, 11 and 12 thereof.

55 A voice-coil 13 is mounted upon and encircles a member of each of the pole-pieces defined by the several cross bars 14 of the laminations, as clearly illustrated in Fig. 2. The voice-coils are so wound and interconnected that the magneto-motive forces engendered thereby are always in series-aiding relation, insofar as the magnetic circuit comprising the elements 8, 10, 12 and 11 of the laminated pole-pieces are concerned, when voice-currents flow therein. The varying flux is confined entirely to the pole-pieces,

the direction thereof corresponding to one direction of voice-currents flow being indicated in Fig. 2 by the arrows 15, and does not traverse the field-magnet.

Conversely, a variation in the flux from the field-magnet, in the event that the said magnet is provided with a field-winding, or otherwise, will not induce electric-currents in the armature in such directions as to cause a movement thereof longitudinally of the gap.

75 Each of the outermost laminations or end plates of the pole-piece assemblies 2 is provided with a projecting lug 16.

80 A thin, flat armature 17 of conductive, non-magnetic metal is resiliently mounted in the air-gaps 6 and 7, defined by the pole-pieces 2, the mounting means for the armature being constituted by a plurality of arms 18 integral therewith, which arms extend at right angles to the plane of the armature as clearly shown in Fig. 6. The armature is preferably stamped from copper or aluminum sheet having a thickness of approximately 40 mils.

85 Each of the arms has an intermediate part which is stiffened by a plurality of bent-up elements 20, and has a resilient portion 21 adjacent to the free end thereof. An opening 22 is formed in each of the free ends of the arms 18 for mounting purposes.

90 The openings 22 in the free ends of the arms 18 are aligned with corresponding openings in the lugs 16 provided on the outermost laminations of each pole-piece assembly. A clamping bolt 23 extends through each pair of aligned openings. Electrical contact between the arms 18 and the lugs 16 is prevented by surrounding each of the clamping bolts 23 with an insulating bushing 24. The openings 22 in the arms 18 are made slightly greater in diameter than the bolts 23, in order that the armature may be easily centered in the air-gaps.

95 The armature is provided with a plurality of elongated openings 30 for a purpose which will hereinafter be referred to, or it may be so made that the openings are substantially semi-ovals, as shown in Fig. 9.

100 One edge of the armature is provided with a lug 31 to which a metal cup 32, or a spider, may be soldered for the purpose of imparting motion to a diaphragm 33.

105 When the voice-coils 13 of my improved loud-speaker motor, are energized from any convenient source of alternating currents, at audio-frequencies, potentials are so induced in the armature 17 that electric-currents tend closed through the portions of the armature defined by the openings 30 as shown by the arrows in Fig. 4. The circuit therefor being closed through the portions of the armature between the openings and the upper and lower edges of the said armature, additional eddy-currents (illustrated in Fig. 5) also tend, instantaneously, to flow across these outer portions of the armature. The addi-

tional eddy currents, however, as illustrated in Fig. 5, exert no appreciable influence on the operation of the device since the effect produced by the current in one direction will be substantially neutralized by the effect produced by the current flowing in the opposite direction at the same time.

Since it is clear that the steady flux is always in the same direction, in each of the air-gaps the reaction between the said flux and the electric-currents in those portions of the armature intermediate the extensions of the pole-pieces is in aiding phase. The armature, accordingly, moves either up or down, depending upon the instantaneous direction of the voice-current which induces the electric-currents therein, at the frequency of the said voice-currents and with force proportional to the intensity thereof.

20 In the modification illustrated in Fig. 7, I have disclosed a simplified structure capable of operating on the same principles as that of Fig. 1. The magnet structure is laminated and built up of L-shaped transformer steel 25 punchings interleaved to form a substantially closed magnetic path except for a narrow air gap wherein to support an armature of the type disclosed in Fig. 8. The armature referred to comprises a punching from a thin 30 sheet of preferably non-magnetic material such as copper or aluminum and of substantially the shape shown. A slot in the armature along its longer axis divides the armature into substantially two sections and acts 35 as an open circuit to the passage of eddy currents which are prone to develop in a system as shown.

In the armature disclosed in Fig. 9, a more efficient means is provided for opposing the 40 development of eddy currents therein. This comprises the provision of a plurality of concentric narrow slits 39 of horse shoe shape terminating close to the center line of the armature. This construction permits of the 45 armature being punched as a one piece affair. The unbroken center line portion of the armature will not destroy the effect sought to be obtained by the slotted structure because the potentials induced at points along the center 50 line are of the same potential and consequently no eddy currents will be caused to flow.

Another method of constructing an armature to give similar results is to wind narrow 55 flat ribbon wire into a single layer pancake coil of a size comparable to that of an armature, a thin solution of water glass or other insulating material being interposed between turns of the wire to perform the function 60 attributed to the slits in the punched armatures described above.

As remarked in conjunction with the description of the structure of Fig. 7 and its component parts, the armature 36 is provided 65 with a stem 38 upon which to mount a dia-

phragm 40 of any desired type. In the ribbon wound type of armature, the stem may extend across and be embedded in the surface of the armature to add to the mechanical strength of the structure.

In assembling the speaker motor illustrated in Fig. 7, the armature 36 is suspended in the air gap with its upper half opposite the pole faces.

A pair of serially connected coils 41 and 43 are mounted, one on each pole piece as shown. The structure so far as described is very suitable when employed in combination with microphonic pick up devices for phonographs or the like wherein the direct current or polarizing component is of a comparatively large magnitude, of the order of one ampere or so. The circuit arrangement would comprise a source of direct current potential, a microphonic pick up device and the speaker 85 motor described above, all connected in series arrangement. By reason of the comparatively large direct current or polarizing component present, it is entirely feasible to pass both currents through the coils of the motor 90 and obtain efficient results.

When employed, however, in connection with radio receiving sets or the like, it is not advisable to pass both the polarizing and voice current through the same coils. The 95 direct current component in this case would be of the order of 1/50 of an ampere, so that a coil of considerably larger number of turns would be required to create the desired number of ampere turns for polarizing purposes. Such a large number of turns would increase the coefficient of self induction to such an extent as to render it unfit as a voice-coil. Therefore, it will be desirable under the circumstances to provide separate voice coils 100 to be wound preferably upon the field coils, or as an alternative, one of the coils disclosed may be employed as a polarizing coil whereas the other coil may be designed as a voice coil.

The embodiment wherein a pair of voice coils is utilized, is admirably adapted for use with radio receivers employing a stage of push-pull amplification. When so employed, each coil will comprise the load on one of the tubes, which tubes are in push-pull arrangement. The voice coils may be either connected directly in the plate circuit of the tubes or be inductively coupled thereto.

One means of supporting the armature in its proper position within the air gap of the device illustrated in Fig. 7 is disclosed in Figs. 10 and 11 of the drawings.

The armature indicated by the reference numeral (36) is held in spaced relationship to the pole faces by means of strips 45 of suitable fibrous material, mounted on the pole pieces at desirable locations. Among the materials suitable for the purpose may be mentioned loose graphited textile or felt,

the graphite serving as a dry lubricant. The strips referred to above may comprise two parts, one of which serves to space the armature with respect to a pole face and the other part functions to prevent axial shifts of the armature. Elements 47 of insulating material riveted or otherwise secured to the armature serve to clamp the fibrous strips to maintain them in their proper position.

10 An alternative method of supporting the armature 36 in operative position is disclosed in Fig. 12. This differs from that disclosed with reference to Figs. 10 and 11 in that the spacing strips may be attached to the armature 36 and in lieu of the clamping elements 47, two strings 49 of proper length may be attached, one at each end of the armature and extended over corresponding pulleys 51 whereby they may be held in tension by the 20 application of suitable forces.

By reason of the fact that the armature may be made thin and the air-gaps correspondingly narrow, the magneto-motive force required to produce a certain permanent induction in the air-gap, is smaller than the magneto-motive force required to produce this permanent induction in the wider air gap of electro-dynamic loud speakers which accommodate a movable coil. Thereby 30 by a smaller amount of magnet steel is required.

A loud-speaker motor constructed according to my invention is, further, quite advantageous in that it may be given a total thickness not substantially greater than the thickness of the fixed magnet portion thereof. This peculiarity of construction is an important feature of my invention inasmuch as it enables the manufacture of a loud-speaker, 35 the front to back dimension of which may be made sufficiently small to adapt the device for wall mounting, even though it is entirely enclosed in a cabinet or the like.

Although I have shown and described certain specific embodiments of my invention, 45 I am fully aware that many modifications thereof are possible. My invention, therefore, is not to be restricted except insofar as is necessitated by the prior art and by the spirit of the appended claims.

I claim as my invention:

1. In combination, a magnetic structure comprising a fixed magnet and a plurality of laminated pole-tips defining a narrow, 55 substantially rectangular air gap, a coil associated with each pole-tip and a substantially flat, non-magnetic, conductive armature mounted in said air gap for movement longitudinally thereof.

60 2. An armature for a loud-speaker motor comprising a substantially flat, conductive element of non-magnetic material provided with integral supporting lugs extending outwardly from the edges thereof, said lugs each 65 having a rigid portion and a flexible portion,

the flexible portion being adjacent to the free extremity thereof.

3. In combination, a magnetic structure comprising a plurality of laminated pole-tips, the outermost laminations of each pole-tip being modified to provide lugs adapted to support an armature. 70

4. In a loud-speaker actuating motor, a permanent magnet, a plurality of pole pieces affixed to said magnet and extending toward each other to define a narrow, substantially rectangular air gap, each pole piece being constituted by a plurality of h-shape laminations, and a coil individual to each pole piece, each coil being disposed around the element 80 of its associated pole piece defined by the cross bars of the h-shape laminations thereof. 75

5. In a loud-speaker actuating motor, a permanent magnet, a plurality of laminated, h-shape pole pieces affixed to said magnet, the laminations of said pole pieces being so disposed with respect to each other as to define a plurality of narrow substantially rectangular air gaps, and a substantially flat, 90 conductive, non-magnetic armature resiliently suspended in said gap, said armature being provided with an elongated opening intermediate the edges thereof. 95

6. In a loud-speaker motor, a field magnet, a plurality of pole-pieces affixed to said magnet to define an air-gap and means for causing the flux in said pole pieces and said gap to vary, the configuration of said pole-pieces being such that a substantially complete magnetic circuit is provided thereby for the varying flux. 100

7. In a loud-speaker motor, a field magnet, a plurality of h-shape pole-pieces affixed to said magnet to define an air-gap, and means for causing the flux in said pole-pieces and said gap to vary, the configuration of the said pole-pieces and their association with said magnet being such that the varying flux is prevented from traversing the major portion 110 of said field magnet. 105

8. In a loud speaker actuating motor, a magnetic circuit defining an air gap, an armature, only a portion of which lies in said air gap, means for generating a current in that portion of said armature lying outside of said air gap but parallel to the portion in said air-gap and means for directing said current into that portion of the armature located in the air gap. 115 120

In testimony whereof, I have hereunto subscribed my name this 24th day of October, 1930.

JURJEN S. HIGH.
